US00D719022S

(12) **United States Design Patent**
Van Den Wouwer et al.

(10) **Patent No.:** **US D719,022 S**
(45) **Date of Patent:** **** Dec. 9, 2014**

(54) **CONTAINER LID**

(75) Inventors: **Chris Van Den Wouwer**, Mortsel (BE); **Andrew Peter Heidel**, Cincinnati, OH (US); **Gian DeBelder**, Schelle (BE); **Gil Palmon**, Cincinnati, OH (US); **Christopher Robert Kopulos**, Cincinnati, OH (US)

CA 101564 3/2004
CA 119729 2/2008

(73) Assignee: **The Procter & Gamble Company**, Cincinnati, OH (US)

FOREIGN PATENT DOCUMENTS

(**) Term: **14 Years**

OTHER PUBLICATIONS

(21) Appl. No.: **29/411,075**

U.S. Appl. No. 29/388,970, filed Apr. 5, 2011, Chris Van den Wouwer et al.

(22) Filed: **Jan. 17, 2012**

Primary Examiner — Ian Simmons

Assistant Examiner — Dana L Meyrow

(74) Attorney, Agent, or Firm — Gregory S. Darley-Emerson; Steven W. Miller

Related U.S. Application Data

(62) Division of application No. 29/388,970, filed on Apr. 5, 2011, now Pat. No. Des. 661,994, which is a division of application No. 29/341,567, filed on Aug. 7, 2009, now Pat. No. Des. 637,912.

CLAIM

The ornamental design for a container lid, as shown and described.

(51) **LOC (10) Cl.** **09-01**

(52) **U.S. Cl.**

USPC **D9/449; D9/435**

(58) **Field of Classification Search**

USPC D9/516, 529–530, 537, 539–540, D9/542–543, 549–551, 563–564, 571–572, D9/575, 435, 446–447, 449; 215/306, 215/382–385; 220/375, 810, 660, 669, 675

See application file for complete search history.

DESCRIPTION

FIG. 1 is a top perspective view of a portion of the container lid embodying our new design;

FIG. 2 is a bottom perspective view of the container lid;

FIG. 3 is a front view of the container lid;

FIG. 4 is a rear view of the container lid;

FIG. 5 is a left side view of the container lid;

FIG. 6 is a right side view of the container lid;

FIG. 7 is a top view of the container lid; and,

FIG. 8 is a bottom view of the container lid.

Only the surfaces with applied surface shading are included in the claimed design. The broken lines in the drawings and those surfaces without surface shading illustrate the portions of the design that form no part of the claim. The broken lines shown on surfaces with applied surface shading represent unclaimed lines on claimed surfaces and form no part of the claimed design.
